Primary Examiner — Michael A. Pratt*Assistant Examiner* — Adam C Mager(74) *Attorney, Agent, or Firm* — Lewis Brisbois Bisgaard & Smith LLP(57) **CLAIM**

The ornamental design for a rack shade, as shown and described.

DESCRIPTION

FIG. 1 is a perspective view of the rack shade showing the new design in use;

FIG. 2 is a front perspective view thereof;

FIG. 3 is a front elevation view thereof;

FIG. 4 is a rear elevation view thereof;

FIG. 5 is a top plan view thereof;

FIG. 6 is a bottom plan view thereof;

FIG. 7 is a right side elevation view thereof;

FIG. 8 is a left side elevation view thereof; and,

FIG. 9 is a detailed view of one of the straps of the rack shade.

The broken lines shown are included for the purpose of illustrating the unclaimed portions of the article and the article's environment and form no part of the claim.

1 Claim, 5 Drawing Sheets(56)
